Primary Examiner — Austin Murphy**CLAIM**

The ornamental design for a touch screen medical card reader, as shown and described.

DESCRIPTION

FIG. 1 is a top perspective view for a touch screen medical card reader showing my new design;

FIG. 2 is a front side view thereof;

FIG. 3 is a back side view thereof;

FIG. 4 is a left side view thereof;

FIG. 5 is a right side view thereof;

FIG. 6 is a bottom side view thereof;

FIG. 7 is a top side view thereof;

FIG. 8 is a bottom rear perspective view; and,

FIG. 9 is a top rear perspective view.

The broken lines in FIG. 1 is a medical information card shown in broken lines for illustrative purposes only and forms no part of the claimed design.
